DESIGN FOR A SHOE

Harry Le Roy Sutcliffe, New York, N. Y.

Application July 23, 1941, Serial No. 102,375

Term of patent 3½ years

To all whom it may concern:

Be it known that I, Harry Le Roy Sutcliffe, a citizen of the United States of America, residing in New York city, county of New York, and State of New York, have invented a new, original, and ornamental Design for a Shoe, of which the following is a specification, reference being had to the accompanying drawing, forming part thereof.

Fig. 1 is a plan view of a shoe showing my new design.

Fig. 2 is a perspective view thereof.

My design for a shoe is characterized by the specific ring-like element of ornamentation on the vamp portion of the type of a shoe as shown, said element of ornamentation having a twisted appearance and of a size which substantially covers the entire toe portion of the shoe.

I claim:

The ornamental design for a shoe, substantially as shown and described.

HARRY LE ROY SUTCLIFFE.
